I. A. BAUM

BUILDING ELEMENT

Filed Dec. 27, 1927

Patented Oct. 9, 1928.

1,686,724

UNITED STATES PATENT OFFICE.

ISAAC A. BAUM, OF CHICAGO, ILLINOIS.

BUILDING ELEMENT.

Application filed December 27, 1927. Serial No. 242,632.

My invention relates to buildings and particularly to an element adapted for use in several locations. In one adaptation the construction is adapted for use as a window stool, and in another adaptation as a base board. A fundamental characteristic is that the element may be pre-formed either in composition material or marble, then placed in position and combined with a plaster ground and plaster terminal in a permanent position.

By the use of an element such as described herein, the labor connected with installation is materially lessened and a highly satisfactory construction is assured.

The invention will be more readily understood by reference to the accompanying drawing in which—

Fig. 1 is a sectional view through a window sill and stool to which my invention has been applied, and

Fig. 2 is a sectional view through a base board and adjacent construction.

Referring particularly to Fig. 1, it will be seen that my invention comprises a stool 10 which may be of composition material moulded to the proper shape. Along one marginal edge and projecting into a space on the lower surface of the element is a continuous strip 11, a perforated flange 12 of which is moulded into the cementitious material. In the construction shown, the strip is doubled and then redoubled on itself to provide the rearwardly projecting tongue 13. A retaining clip 14 having a rebent flange 15 is secured to a base or sill 16 by means of nails 17. This clip is adapted to receive the tongue 13 and to securely hold the stool against vertical displacement.

At the forward edge of the stool, I provide a clip 18, the apertured flanges 19 of which are moulded in the material composing the stool. The downwardly projecting edge or flange 20 of the clip is adapted to lie alongside of the sill or base 16, and to be secured thereto by means of nails 21. Metal lath is indicated at 22 and performs the usual function. The portion 19 of the strip is bent and rebent to provide the triangular nose 23, which projects downwardly from the lower face of the stool 10 and provides a plaster terminal and a plaster ground. Plaster, indicated at 24, is

caused to flow beneath the diagonal part 55 25 which acts as a key; the flat vertical surface acts as a ground for leveling the surface of the plaster.

In the construction illustrated in Fig. 2, the elements remain similar. The base board 60 26 may be of moulded form, having the male member 27 of the attaching element cast in the body of the cement; the female member 28 of the attaching combination is secured to the wall by means of nails 29, the rebent 65 portion 30 providing a slot for the reception of the downwardly projecting flange 31 of the attaching element.

At the upper end, the attaching clip has a triangular portion 32 that is moulded in 70 the body of cement, the rearward vertical flange 33 serving as a means for attachment to the adjacent wall. The terminal portion of the triangular part 32 projects vertically above the upper limit of the base-board as at 75 34, and is then rebent as at 35 to provide a plaster terminal or plaster key. The part 34 serves as a ground. In application of either 80 of the two devices illustrated, the attaching clip is secured in position, no particular care being required to position the clip. Thereafter the stool or base board as the case may be, constructed as shown, is placed and moved by sliding action into position where the male and female elements of the attaching device are in proper co-operation. Thereafter the free flanges on the opposite end of the device are nailed to the adjacent wall. No further work is necessary in order to insure proper positioning of the element relative to the wall. 90

The base board or stool may be composed of cementitious material as shown, or of marble or similar material. In the latter case, the marble will be shaped to provide 95 suitable recesses for the reception of the clips and the clips thereafter permanently held in place by means of cement or plaster of Paris.

I claim:

1. A building element comprising, in combination, a strip providing a tongue, and an attaching clip, both moulded into the element at opposite sides thereof, and means on the clip providing a plaster terminal and 105 ground.

2. In combination a body of cementitious material attaching clips moulded into the

material, one of said clips providing a plaster ground and an undercut surface acting as a plaster key.

3. A base board or window stool composed of a body of rock-like material, an attaching element moulded into said material, said element having a flange adapted to act as a means of attachment to an adjacent wall and also having a projecting portion acting as a plaster terminal and as a plaster ground.

4. A base board or window stool consisting of a body of rock-like material, clips seated in said material near each side margin thereof, and means co-operating with said clips providing for attachment to a wall

and for the co-operation of the plaster therewith.

5. In a base board or window stool, the combination of a body of material, a clip moulded therein and having a tongue lying in a plane with the unexposed flat surface of said base board or window stool, a co-operating clip adapted to be secured to an adjacent wall and having a recess adapted to be occupied by said tongue on movement of the base board or stool in a line parallel with the face of the wall to which it is attached.

In testimony whereof I have affixed my signature.

ISAAC A. BAUM.
